UNITED STATES PATENT OFFICE

HOWARD M. LEONARD, OF SOUTH BEND, INDIANA, ASSIGNOR TO GERNANDT MOTOR CORPORATION, OF CHICAGO, ILLINOIS, A CORPORATION OF ILLINOIS

INJECTION ENGINE

Application filed June 2, 1927. Serial No. 195,960.

This invention relates to engines, and is illustrated as embodied in a two-cycle internal combustion engine of the injection type. An object of the invention is to provide simple but efficient means for injection of the fuel, the fuel preferably being mixed with and vaporized with air, or exhaust gas, or other fluid medium.

One feature of the invention relates to injecting the fuel mixture through a narrow annular space formed around the head of a novel distributing device, shown as being threaded into the side wall of the engine cylinder and with the fuel mixture forced under pressure behind the head and around the head into the engine cylinder for ignition by the hot compressed air contained therein at that time.

Another feature has to do with preventing leakage around the fuel plunger, by forming the plunger of sections yieldingly forced against the surrounding cylinder wall, and having novel operating means including a packing of bearing metal or the like sealing the joint between the two sections.

The above and other objects and features of the invention, including various novel combinations and desirable particular constructions of the parts, will be apparent from the following description of one illustrative embodiment shown in the accompanying drawings, in which:

Figure 1 is a vertical section through part of the upper portion of the engine cylinder and piston, and through the novel fuel-injecting means;

Figure 2 is a partial section on the line 2—2 of Figure 1, showing the distributing device in elevation;

Figure 3 is a view corresponding to Figure 1, but showing a modified form of fuel distributor and a modified form of compression plunger;

Figure 4 is a section corresponding to Figure 2, but on the line 4—4 of Figure 3, and showing the modified fuel distributor in elevation; and

Figure 5 is a partial section corresponding to a portion of Figure 1 or Figure 3, but

showing a different modification of the fuel distributing device.

The engine illustrated in Figure 1 includes an engine cylinder 10, in which is arranged an engine piston 12 of any desired form. According to one feature of the invention, there is in the side wall of the engine cylinder a recess cooperating with the head of a novel distributing device 14, which head is slightly smaller than the recess so that there is an annular space between them through which the fuel mixture is forced as a hollow cylindrical spray into the engine cylinder. The distributing device 14 has projections 16 on the back of its head, and is threaded into the cylinder wall until these projections prevent further movement, thus defining behind the head a space or fuel pocket 18 into which a passage 20 opens.

Adjacent and paralleling the engine cylinder, there is a compression cylinder containing a novel fuel-injecting plunger including longitudinally separated sections 22 and 24, which may be urged apart against the cylinder wall by springs 26, and which have on their adjacent flat faces one or more grooves 28 forming a fuel passage from the upper end of the plunger, and continued as a cross passage through section 24 which cross passage registers with passage 20 when the plunger reaches the end of the compression stroke. I prefer to form the upper end of the compression plunger of reduced diameter, and to reduce the compression cylinder accordingly, so that at the end of the compression stroke the mixed fuel and air or exhaust gas is forced around this reduced plunger portion with a great deal of turbulence, thus aiding in vaporizing the fuel.

At their lower ends, sections 22 and 24 are formed with registering semi-spherical recesses receiving a semi-spherical head 30 on an operating plunger 32 reciprocated by a cam or an eccentric or the like. Above the head 30 there is a packing 34, preferably of soft metal such as a hard babbitt, which is forced against the walls of the semi-spherical recesses with a wedging action when it is compressed by head 30 on the compression stroke of the plunger, aiding the springs 26.

in forcing the sections 22 and 24 against the cylinder wall and also sealing the joint between the sections and preventing seepage of fuel downwardly between the sections.

5 In operating, during the downward stroke of the plunger, a charge of fuel is introduced into the compression cylinder above the plunger by any suitable means (not shown). At the end of this downward stroke, the 10 upper end of the plunger clears the passage 20 just before the end of the power stroke of piston 12, so that hot exhaust gas under considerable pressure fills the compression cylinder above the plunger, and during the upward stroke of the plunger the fuel is vaporized in this gas by the heat contained in the gas, aiding the heat of compression. At the end of the upward stroke, and just before piston 12 reaches the end of its upward 15 stroke in compressing the air charge, passage 28 discharges the fuel through the annular space around the distributing device 14, into the engine cylinder, where the fuel is at once ignited.

25 In the arrangement of Figures 3 and 4, there is a distributing device 36 having a conical head, and which can be turned to adjust the size of the annular space around the head, and which may be formed with 30 cross passages 38 if desired. The head of the device 36 is slotted for engagement with a screw driver.

The plunger, in this arrangement, not only has a reduced portion 40 at its extreme end, 35 but also a portion slightly smaller in diameter than the cylinder, as shown at 42, to provide an annular space communicating by radial passages 44 with a central longitudinal passage 46 leading, by a cross passage 48, 40 to the side of the plunger, the plunger in this case being in one piece instead of in sections as in Figure 1. When the plunger reaches the upper end of its stroke, passage 48 registers with a passage 50 opening into 45 the space behind the head of the distributor 36. This fuel-feeding means operates in the same general manner as that of Figures 1 and 2. In Figure 5 is shown a slightly different form of distributor 54.

50 While several illustrative constructions have been described in detail, it is not my intention to limit the scope of the invention to those particular constructions, or otherwise than by the terms of the appended claims.

I claim:

1. Fuel-injecting means comprising, in combination with an engine cylinder, a distributing device having a head cooperating with a part of the wall of the cylinder to form an annular injection space, said device provided with means contacting said wall to definitely define said space together with means for forcing fuel under pressure be-

neath said head and thence through said annular space into the engine cylinder.

2. Fuel-injecting means comprising, in combination with an engine cylinder having a cup-shaped recess in its side wall, a distributing device having a cylindrically shaped head fitting within said recess and cooperating therewith to form an annular injection space, a compression cylinder communicating with the space behind said head, and a plunger in the compression cylinder for forcing fuel through the annular space into the engine cylinder.

3. Fuel injection means comprising, in combination with an engine cylinder having a cup-shaped recess in its side wall, a distributing device threaded into the cylinder wall, said device provided with a cylindrically shaped head of smaller diameter than the recess in the cylinder wall to define an annular injection space for fuel therethrough.

4. Fuel injection means comprising, in combination with an engine cylinder having a cup-shaped recess in its side wall, a distributing device having a cylindrically shaped head of smaller diameter than said recess and fitting therein to provide an annular injection space for the fuel to be forced therethrough, said cylindrically shaped head provided on its side next to the cylinder with projections contacting with the bottom of the aforementioned recess.

5. A distributor for fuel injection unit comprising a shank for securing the distributor in a recess, a disc portion adapted to deflect fuel around its periphery, and a projection on the disc forming a stop adapted to contact with the bottom of the recess and cause the disc to form one wall of a fuel passageway.

In testimony whereof, I have hereunto signed my name.

HOWARD M. LEONARD.
